UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

REFRIGERATING APPARATUS

Application filed March 24, 1928. Serial No. 264,505.

This application relates to a refrigerating apparatus, and more particularly to a refrigerator in which the refrigerating machinery is resiliently mounted and flexibly suspended.

5 An object of this invention is to provide a refrigerator in which the moving parts of the refrigerating system are resiliently mounted or flexibly suspended to prevent the transmission of vibration to the relatively 10 stationary parts.

Another object of this invention is to provide a resilient support for machinery adapted to be used in a refrigerating system.

Another object of this invention is to provide 15 a resilient support for machinery having a rotary member and a reciprocating member.

Another object of this invention is to provide 20 a flexible suspension for machinery adapted to be used in a refrigerating system.

Another object of this invention is to provide 25 a flexible support particularly adapted for machinery having a rotary member and a reciprocating member.

Further objects and advantages of the 30 present invention will be apparent from the following description, reference being had to the accompanying drawings, wherein a preferred form of the present invention is clearly shown.

In the drawings:

Fig. 1 is a side elevation of a refrigeration system showing the compressor and motor more or less in detail mounted on a resilient and flexible support, and with the remainder of the system shown diagrammatically;

Fig. 2 is an end elevation of the motor and compressor and the resilient and flexible support therefor;

Fig. 3 is an enlarged detail view taken along the line 3—3 of Fig. 1, and

Fig. 4 is an enlarged detail cross-sectional view of the strap fastening means taken along the line 4—4 of Fig. 1.

A refrigeration system, in which features 45 of my invention are embodied, is generally designated as 20. If of the compressor-condenser type, it may comprise a motor 21 driv- 50 ingly connected to a compressor 22. The compressor 22 then delivers compressed re-

frigerant through the line 23 to the condenser 24. Liquefied refrigerant, in this type of system, is delivered to receiver 25 from the condenser 24. The receiver 25 delivers liquid refrigerant to an evaporator 26 through line 55 27. The entrance of refrigerant to the evaporator 26 may be controlled by a float valve, not shown. The evaporator 26 delivers evaporated refrigerant through the line 28 back to the crankcase of the compressor 22. The 60 low pressure line 28 may be connected by means of a branch 29 to an expansible, bellows 30 which operates a snap switch 31 controlling the starting and stopping of the motor 21.

The motor 21 and compressor 22 may be resiliently mounted and flexibly suspended. The lines 23 and 28 may have resilient portions so that vibrations of the compressor are not transmitted to the remainder of the 70 system. In the preferred embodiment, the motor 21 and compressor 22 are mounted on an inverted channel-shaped platform 40. This platform 40 may have an ear 41 upwardly directed and, if desired, this ear 41 75 may be struck from the floor 42 of the platform 40 so that it is integral with the platform. The upper end of the ear 41 is provided with an enlargement 43 having an opening formed therein to receive a bar 44. The bar 44 may be keyed at 45 to the ear 41. At the ends of the bar 44 may be keyed 80 flat arch-shaped springs 46. The springs may be formed by flat resilient portions 47 having, for instance, castings 48 bolted thereto which are provided with openings 85 for the ends of the bar 44. The springs 46 may be keyed to the bar 44 by means of keys 49. Thus, the platform 40 is rigidly connected to the rocker-like springs 46.

The springs 46 are adapted to rock on straps 50 which may be suspended at each end by means of supports 51 which, if desired, may be resilient. Near the ends of the springs 46 these springs may be tied to the straps 50 by means of metal clamps 46^a which may be bent around the springs 46 and the straps 50. These may be provided with teeth 46^b which are adapted to be sunk into the straps 50 to prevent the springs from 100

falling off the straps 50. The supports 51, if resilient, permit a slight amount of freedom in movement of the strap 50.

5 The bar 44 is substantially in the axis of oscillation of the members 21 and 22. The motor 21 drives the compressor 22 preferably through the belt 53. The motor 21, which may be rotary in combination with the compressor 22 which may have a crank 10 turning about the axis 54 tends to impart to the platform 40 a rocking movement about an axis substantially coincident with the bar 44. The straps 50, together with the spring 46 tend to allow a slight rocking 15 movement about the bar 44 and prevent a lateral movement of the platform 40.

Thus I provide a support in which the machinery is mounted on a platform which rocks on a flexible suspension. This rocking movement tends to permit the machinery to take its natural vibration and does not transmit it to the place where it is mounted. The resiliency of supports 51 aid in permitting the natural rocking movement.

25 While the form of embodiment of the invention as herein disclosed constitutes a preferred form, it is to be understood that other forms might be adopted, all coming within the scope of the claims which follow.

30 What is claimed is as follows:

1. In a support for driving and driven members oscillating about a substantially definite axis, the combination of a supporting member, means for floatingly supporting said member substantially about said axis of oscillation, said means including upwardly concave strap members and means connecting said member to said strap.

35 2. In a support for driving and driven members oscillating about a substantially definite axis, the combination of a supporting member, means for floatingly supporting said member substantially about said axis of oscillation, said means including an upwardly concave strap, resilient means on said strap and means connecting said member to said resilient means.

40 3. In a support for driving and driven members oscillating about a substantially definite axis, the combination of a supporting member, means for floatingly supporting said member substantially about said axis of oscillation, said means including a hanger secured to said member, an arc-shaped spring secured to said hanger and an upwardly concave strap on which said arc-shaped spring rests.

45 4. In a support for driving and driven members oscillating about a substantially definite axis, the combination of a supporting member, means for floatingly supporting said member substantially about said axis of oscillation, said means including hanger means secured to said member, arc-shaped springs secured to said hanger means,

and upwardly concave straps supporting said springs, said straps being in turn supported by resilient supports.

5. In a support for driving and driven members oscillating about a substantially 70 definite axis, the combination of a supporting member, means for floatingly supporting said member substantially about said axis of oscillation, said means including hanger means secured to said member, laterally extending strap means, resilient means secured to said hanger means and resting on said strap means and resilient supports secured to the ends of said strap means, said resilient supports being in turn 80 connected to a base structure.

In testimony whereof I hereto affix my signature.

OTTO M. SUMMERS.
